Inventor

Hermon Thomas by
Frederick Thomas, Atty

United States Patent Office.

HERMON THOMAS, OF PHILADELPHIA, PENNSYLVANIA.

Design No. 4,147, dated June 7, 1870.

DESIGN FOR CIDER, WINE, AND OTHER PRESSES.

The Schedule referred to in these Letters Patent and making part of the same.

To all whom it may concern:

Be it known that I, HERMON THOMAS, of Philadelphia, in the county of Philadelphia and State of Pennsylvania, have invented a new and original Design for Cider, Wine, and other Presses, and I do hereby declare that the following is a full and exact description of the same, reference being had to the accompanying drawing.

The nature of my design is fully represented in the accompanying photographic illustration, to which reference is made.

What I claim as my invention is—

The design for a press, as shown.

This specification signed and witnessed this 4th day of May, 1870.

Witnesses: HERMON THOMAS.

FRED. THOMAS,
GEORGE A. STEVENS.
